UNITED STATES PATENT OFFICE.

DOROTHY LOCKWOOD, OF MERTON PARK, AND ALFRED JAMES SEARLE, OF LONDON, ENGLAND.

LINE-STRETCHING APPARATUS.

Application filed December 31, 1926, Serial No. 158,358, and in Great Britain January 27, 1926.

This invention which relates to means for stretching and pulling lines, ropes, wires or the like and retaining same in a taut or pulled condition and is applicable for clothes 5 lines, tennis nets, aerials, wire fences, clamps, lifting devices and other similar purposes or uses, relates to apparatus of the known kind comprising a bifurcated or forked handle whose legs are furnished with exteriorly 10 projecting pins or studs, and a bracket or lug with spaced-apart cheeks adapted to receive said pins or studs and to accommodate the handle between them, the handle thus being pivotally held by the bracket or 15 lug to swing in a vertical plane, the construction being such that in swinging down the handle, to which latter the line or the like is suitably connected, in order to stretch or pull the line, the point of connection of 20 the latter with the lever passes over a vertical line through the lever pivot, that is to say, passes over a dead-centre position. In such apparatus a pulley has been provided above the handle member, over which 25 the line passes, said pulley being mounted on the same vertical structure as that to which the handle-carrying lug or bracket is attached. The invention particularly refers to apparatus of the foregoing kind 30 wherein the handle legs are of a springy nature, so that by pressing same towards one another the pins or studs thereon will pass out of the bracket or lug cheeks, permitting detachment of the handle. 35 Hitherto, in apparatus of the foregoing kind, the line or the like has been directly attached to the lever, so that in swinging the latter down in order to stretch or pull the line, said line itself passed over the lever 40 pivot. With such an arrangement, if the lever is not mounted to swing exactly in the plane of the line, said line will be apt to shafe on the handle and wear.

The present invention, which embodies 45 the known features above set forth, is characterized in that there is pivotally connected to the forked lever, between the legs thereof, a link member to which there is connected the line or the like, the construction being 50 such that the distance between the point of connection of the link with the lever and the point of connection of the line with the link is greater than the distance between the point of connection of the link with the 55 lever and the lever pivot, so that when the

lever is swung down to its locking position, the link, but not the line itself, passes across the lever pivot.

In order that the said invention may be the more readily understood, drawings are 60 appended illustrating various constructions of apparatus in accordance therewith, and wherein:

Figure 1 is a general view illustrating the various parts employed according to one 65 construction with the line in its slackened position; and,

Figure 2 is a similar view showing the line in its tightened position.

Figure 3 is a plan view of the lever, the 70 bracket carrying same and the intermediate link member, shown in Figure 1.

Figure 4 is a similar view to Figure 2 of a modified construction of apparatus.

Figure 5 is a detail side view hereinafter 75 described, illustrating a modified method of connecting the link to the lever.

Figures 6, 7 and 8 illustrate a modified form of lever-carrying bracket constructed to provide for adjustability of the lever 80 pivot.

Referring to Figures 1, 2, 3 and 4 of the drawings, the apparatus illustrated therein comprises a wooden or metal lever 1 formed to a handle shape at its outer end 2. Said lever is bifurcated to form two legs, and is pivotally mounted within the spaced-apart 85 cheeks 3 of a bracket or lug member 4. Two pivot pins 5 are furnished, each extending through one leg of the handle and one cheek 90 of the lug or bracket 4. Neither of said pivots extend across the space between the two legs of the lever. Between the legs of the lever 1 there is pivotally mounted a link member 6, serving as an intermediate member 95 between the line 7 and the lever, and the connection of such link member to the lever is such as to allow of expeditious adjustment to alternative points of fixture.

In the construction shown, a plurality of 100 alternative holes 8 are formed through the lever at different radii from the lever pivot and the link 6 is connected to the lever 1 by means of a detachable pin 9 adapted to engage in any suitable one of said holes. The link 6 at its outer end carries a pulley 10 mounted between spaced-apart cheeks 11. The line 7 passes from a point of fixture, that is to say, a hook, loop or the like 12, around the pulley 10, then up to around 110

another pulley 13 mounted above the lever unit above described, between the cheeks of a bracket 14.

The aforesaid parts are mounted to one and the same wall surface and the lever unit and the upper pulley 13 may be separate to one another for attachment directly to a wall surface, as shown in Figures 1 and 2. Alternatively, the said two units may form parts of a self-contained member for attachment to a wall; for instance, they may be mounted on a flat wooden panel 15^a, formed with keyhole or other shaped slots adapted to fit on nails driven into a wall, as shown dotted in Figures 1 and 2, or may be mounted on a metal rod 15, as shown in Figure 4.

On another wall surface to which the line 7 is to pass, there is mounted a hook member 16 and a cleat member 17 immediately below said hook member 16, and the line is adapted to pass over the hook and be wound around the cleat when properly adjusted. The hook and cleat 16 and 17 may be constructed for direct attachment to a wall, as shown in Figures 1 and 2, in which case they are furnished with flat base parts, or may form part of a self-contained unit which includes a metal rod 18 on which they are both mounted, as shown in Figure 4.

In the construction of apparatus shown in Figure 4, the rods 15 and 18 are attached to a wall or the like by means of screw eyes 19.

When the line 7 is in its slackened or released position, the lever is in a raised position, as shown in Figure 1, but when the lever is pressed down to the position shown in Figure 2, it pulls and tightens the line which is then held taut with the handle in the down position. The construction and mounting of the lever is such that when the lever is pressed down, its point of connection with the link member 6 passes over the dead-centre; that is to say, the said link member swings over to the opposite side of the lever pivot and the lever becomes locked in the position shown in Figure 2, due to the tensioned pull on the line.

In the modification shown in Figure 5, a pin 21 fixedly carried by the link members 6 and projecting on each side thereof is adapted to engage in any one of a plurality of coincident T-shaped slots 22 formed in the bottom edges of the legs of the bifurcated lever 1.

In another modification, the line could be directly attached to the upper end of the link member 6 instead of passing around a pulley carried thereby.

Further, other modifications may be made without departing from the spirit of the invention as hereinbefore set forth.

It is to be understood that the hook and cleat members above described need not nec-

essarily be employed, but alternatively the line may be secured to a single eye-headed screw or the equivalent driven into the wall.

Owing to the method of mounting the lever between the spaced-apart cheeks 3 of the lugs 4, the two legs of the lever may be pressed together against the natural springiness of said legs a sufficient amount to enable the pivot pins 5 to pass out of the said lug cheeks 3, and thus the lever may be detached. A further advantage obtaining from the use of a bifurcated lever is that a central pull is obtained on the line, wire or the like, owing to the fixture point of said line or wire (either directly or indirectly) being between 89 the lever legs as hereinbefore described.

Figures 6, 7 and 8 of the drawings illustrate a modified form of lever-carrying bracket which we may employ, and said bracket, which is constructed to provide for adjustability as to position of the lever pivot so that primary adjustment as to the tension of the line or wire in its taut position may be made, comprises a flat base part 23 and spaced-apart parallel side cheeks 24 in each of which side walls a plurality of notches or recesses 25 are formed, preferably of part-circular shape to correspond with the shape and diameter of the pins or studs 5 on legs of the handle 1. The said notches or recesses 25 are disposed one above another, all in the same vertical line, and communicate with one another by means of curved or arcuate slots 26, there being one such slot between each two adjacent notches or recesses, the separate slots together forming, in effect, one long continuous slot. The notches or recesses 25 are disposed towards the front edges of the bracket cheeks 24 and the curved slots 26 each lead in a rearward direction away from said notches 25. The curved rear edges 27 of the slots 26 effectively guide the pins or studs 5 of the lever 1 into adjacent upper or lower notches 25 according to in which direction the lever is pressed, but owing to downward opening of the said notches 25, the tension of the wire or rope and the pressure of the sprung legs of the lever against the bracket cheeks 24 will retain the pins or studs in engagement with a particular notch until adjustment to another notch or recess is effected.

The apparatus according to the invention having the slotted bracket giving primary adjustment of the lever besides being applicable generally is particularly suitable for tightening the nets on lawn tennis grounds, in which case the said bracket is affixed to one of the net posts and the net-supporting rope is connected to the link carried by the lever.

We claim:

1. A line stretching apparatus comprising a U-shape bearing bracket adapted to be fixed to a support, a split operating lever 130

pivoted between the sides of said bracket, a work engaging arm pivoted in said split operating lever between its pivot and free end, and a work engaging pulley mounted at the 5 free end of said work engaging arm.

2. A line stretching apparatus comprising a U-shape bearing bracket adapted to be fixed to a support, a split operating lever adjustably pivoted between the sides of said 10 bracket, a working engaging arm pivoted in said split operating lever between its pivot and free end, and a work engaging pulley mounted at the free end of said work engaging arm.

3. A line stretching apparatus comprising 15 a U-shape bearing bracket adapted to be fixed to a support, a split operating lever adjustably pivoted between the sides of said bracket, a work engaging arm adjustably pivoted in said split operating lever between 20 its pivot and free end, and a work engaging pulley mounted at the free end of said work engaging arm.

In testimony whereof we have affixed our signatures hereto this 6th day of December, 1926.

DOROTHY LOCKWOOD.
ALFRED JAMES SEARLE.
